UNITED STATES PATENT OFFICE.

WILLIAM H. BANKS, OF WINTHROP, MASSACHUSETTS.

RAILWAY GUARD FOR STATION PLATFORMS.

Application filed November 15, 1922. Serial No. 601,171.

To all whom it may concern:

Be it known that I, WILLIAM H. BANKS, a citizen of the United States, residing at Winthrop, county of Suffolk, State of Massachusetts, have invented a certain new and useful Improvement in Railway Guards for Station Platforms, of which the following is a specification, reference being had therein to the accompanying drawings.

10 The invention relates to a new and useful improvement in railway guards for station platforms. The invention is especially intended for use in connection with railway platforms in subways and elevated railroads, 15 although it is adapted for use on railway platforms where the tracks are on the surface, whether electric or steam railroads.

In connection with electric railways and subways and in connection with elevated railroads, the tracks are usually laid in a pit 20 between the platforms for the loading and unloading of the passengers. These platforms are usually unguarded along the edge of the road bed, and at busy hours of the day 25 when the platform is crowded with passengers waiting for the cars, there is great danger of those who are standing near the edge of the platform being crowded by those who are behind them and pushed off the 30 platform down onto the track below in front of an approaching car. It is also well known that persons standing near the edge of the platform are sometimes seized with dizziness and fall onto the track, and it is 35 also known that people sometimes attempt to commit suicide by throwing themselves onto the track in front of the approaching car. The object of the present invention is to provide a guard which will to a considerable 40 degree hold back the waiting passengers and which will prevent their crowding in a mass and yet which will readily allow of the passing of the passengers in single file through a plurality of passageways, and 45 which requires no mechanical manipulation.

The invention will be fully understood from the following description when taken in connection with the accompanying drawings, and the novel features thereof will be 50 pointed out and clearly defined in the claims at the close of this specification.

In the drawings, Fig. 1 is a side elevation partly in section of a railway platform equipped with a guard embodying the invention, and showing a trolley car on the track waiting to be loaded.

Fig. 2 is a plan view of the parts shown in Fig. 1.

Fig. 3 is a vertical section on the line 3—3 of Fig. 2.

Fig. 4 is a plan view showing a modified form of guard.

Referring now to the drawings, 1 represents a station platform having an upper surface 2 on which the passengers stand, and having a pit 3 for the road bed in which lie the car rails 4—4, a car being represented at 5. The guard embodying the invention is located on the platform parallel with the edge of the platform and set a short distance 6 away from the edge so as to allow a space 6 between the guard and the edge of the platform of sufficient width for the passengers to easily pass along the platform in front of the guard to enter the car 7 after passing through the guard. The guard consists of a plurality of walls or fences 7, which for convenience will be referred to as fence units, fixedly mounted upon the platform. Said units are parallel 8 with each other, but each individual unit is in a line which is diagonal to the edge of the platform, as clearly shown in Figure 2, and the several units are arranged in a row 85 which is parallel with the edge of the platform. These units are spaced apart from each other forming a passageway 8 of sufficient width to easily allow one person at a time to pass through between any two adjacent units.

Preferably each unit is of a sufficient length and angle of inclination to the front line 9 of the series of units, so that the end 10 of one end of each unit will lap past the opposite end 11 of the adjacent fence when viewed in a line drawn at right angles to the general line of direction of the entire guard and of the edge of the platform. Thus to a person approaching the guard in entering the station to take a car, at first appearance 100 it will look as though there were a closed fence preventing passage. It will be obvious, however, by looking diagonally that a person can pass one at a time through this diagonal passageway, which is always open. 105 There will be a large number of these passageways as there will be a large number of these units extending along in a row, as shown in Figure 2, so as to accommodate a large number of people at one time, but the 110 passengers will be obliged to pass in single file through these several passageways and

in a diagonal direction to the line of the track. This will tend to prevent the mass crowding which occurs when there is no obstruction at all, and while there is a possibility of those in single file behind crowding the one in front, there is far less danger than in the mass crowding. Preferably there is provided a hand grip 14 on the side of the guard.

10 The guard need not be high enough to prevent passengers from seeing over the top sufficiently to see the car and the signs on the car, but should preferably be at least waist high or perhaps shoulder high, 15 enough so that there is no danger of the passenger being pushed over the top of it, and yet not high enough to obstruct his view.

Preferably each unit 7 of the guard is 20 made tight like a tight board fence, in order to be sufficiently strong to withstand being broken. In the modification shown in Figure 4, each unit is composed of a plurality of rods 12. In such case the rods should 25 have a tie rod 13 to tie them together. The lower ends of each unit, whether made of boards or rods, should be securely and rigidly fastened to the floor of the platform. When the platform is made of cement, as is 30 usually the case, the lower ends may be embedded in the cement, as plainly shown in the drawings.

What I claim is:

1. A railway guard for station platforms, 35 comprising a plurality of guard units each disposed in a line which is diagonal to the edge of the railway platform adjacent thereto, the several guard units being parallel with each other and spaced apart sufficiently

to form narrow passages between the adjacent units, the series of units as a whole being in a row parallel with the edge of the railway platform.

2. A railway guard for station platforms, comprising a plurality of guard units each 40 disposed in a line which is diagonal to the edge of the railway platform adjacent thereto, the several guard units being parallel with each other and spaced apart sufficiently 45 to form narrow passages between the adjacent units, the end of each unit at the entrance end lapping past the end of the adjacent unit at the exit end viewed in a line at right angles to the front line of the series 50 of units, the series of units as a whole being in a row parallel with the edge of the railway platform.

3. A railway guard for station platforms, comprising a plurality of guard units each disposed in a line which is diagonal to the 55 edge of the railway platform adjacent thereto, the several guard units being parallel with each other and spaced apart sufficiently to form narrow passages between the adjacent units, the end of each unit at the entrance end lapping past the end of the adjacent unit at the exit end viewed in a line at 60 right angles to the front line of the series of units, the series of units as a whole being in a row parallel with the edge of the railway 65 platform, the guard units being set somewhat back from the edge of the platform so as to afford a narrow unobstructed space between the edge of the platform and the adjacent ends of the several guard units.

In testimony whereof I affix my signature.

WILLIAM H. BANKS.
